APPARATUS FOR THE CONTROL OF HIGH-WAY CROSSING SIGNALS

George R. Pflasterer, Greenville, Pa., assignor to
The Union Switch & Signal Company, Swiss-
vale, Pa., a corporation of Pennsylvania

Application February 23, 1939, Serial No. 257,928

8 Claims. (Cl. 246—130)

My invention relates to apparatus for the control of highway crossing signals, and particularly to apparatus capable of controlling highway crossing signals for a track over which trains operate in both directions, so as to continue the operation of the signal when a train enters a control section in approaching the intersection from one direction after the operation of the signal has been initiated by another train entering another control section in approaching the intersection from the other direction, but which other train reverses direction to vacate the other control section.

An object of my invention is the provision, in apparatus of the character described, of novel and improved means effective to maintain operation of highway crossing signals during momentary losses of train shunt within a control section.

Other objects and advantages of my invention will appear as the specification progresses.

I shall describe one form of apparatus embodying my invention, and shall then point out the novel features thereof in claims.

The accompanying drawing is a diagrammatic view of a preferred form of apparatus embodying my invention.

Referring to the drawing, the reference characters **1** and **1a** designate the track rails of a stretch of railway track over which traffic moves in both directions, and which is intersected at grade by a highway **H**. Located adjacent the intersection is a highway crossing signal **S**, which may be of any suitable type, but which, as here shown, is an audible signal in the form of an electric bell.

The track rails **1** and **1a** are divided by means of the usual insulated rail joints **2** into relatively long outer sections **D—E** and **F—G** separated from each other by a relatively short section **E—F**. Sections **D—E** and **F—G** will usually be of such length suitable to provide an adequate warning period to highway users of the approach of a train to the intersection. Section **E—F** will usually be of such length as to completely include the intersection.

Sections **D—E**, **E—F** and **F—G** are provided with track circuits comprising in each instance a suitable source of current, such as track battery **3**, connected across the track rails at one end of the section and a track relay, designated by the reference characters **1TR**, **2TR** and **3TR**, respectively, connected across the track rails at the other end.

The reference characters **1TPS** and **3TPS** designate auxiliary relays, one for each track

relay **1TR** and **3TR**, respectively, for the outer track sections **D—E** and **F—G**. Relay **1TPS** is normally energized over a stick circuit passing from one terminal **B** of a suitable source of current, such as a battery not shown, through front contact **5** of relay **1TR**, front contact **6** of relay **1TPS**, and the winding of relay **1TPS** to the other terminal **C** of the source of current. Relay **3TPS** is normally energized over a stick circuit passing from terminal **B** through front contact **7** of relay **3TR**, front contact **8** of relay **3TPS**, and the winding of relay **3TPS** to terminal **C**. Relay **1TPS** is provided with a first pick-up circuit which may be traced from terminal **B** through back contact **31** of relay **2TR**, and the winding of relay **1TPS** to terminal **C**. Relay **3TPS** is provided with a first pick-up circuit passing from terminal **B** through back contact **32** of relay **2TR**, and the winding of relay **3TPS** to terminal **C**. Relays **1TPS** and **3TPS** are provided each with a second pick-up circuit which will be pointed out hereinafter.

The reference characters **1TER** and **3TER** designate time element relays, one for each track relay **1TR** and **3TR**, respectively. The time element relays **1TER** and **3TER** may be of any suitable type, such as, for example, the type described in United States Letters Patent No. 2,114,895, granted on April 19, 1938, to H. E. Ashworth for Thermal relays. These relays are each provided with a normally open contact which closes within a predetermined time interval of, say, 10 seconds after the relay is energized. The circuit for energizing relay **1TER** may be traced from terminal **B** through front contact **5** of relay **1TR**, the operating element of relay **1TER**, and back contact **10** of relay **1TPS** to terminal **C**. The circuit for energizing relay **3TER** may be traced from terminal **B** through front contact **7** of relay **3TR**, the operating element of relay **3TER**, and back contact **11** of relay **3TPS** to terminal **C**. Each time element relay **1TER** or **3TER** cooperates with its associated track relay to provide the second pick-up circuit for the auxiliary relay **1TPS** or **3TPS**, respectively, and to prevent in a manner to be described in detail presently, a momentary loss of train shunt in control section **D—E** or **F—G** from effecting the operation of signal **S**.

The second pick-up circuit for relay **1TPS** may be traced from terminal **B** through front contact **5** of relay **1TR**, contact **12** of relay **1TER**, and the winding of relay **1TPS** to terminal **C**. The second pick-up circuit for relay **3TPS** passes from terminal **B** through front contact **7** of relay **3TR**, contact **13** of relay **3TER**, and the winding of relay **3TPS** to terminal **C**.

55 The reference characters **1TPS** and **3TPS** designate auxiliary relays, one for each track

- tact 13 of relay 3TER, and the winding of relay 3TPS to terminal C.
- The reference character CR designates a signal operating relay preferably provided with slightly slow releasing characteristics, for governing the operation of signal S. Relay CR is normally energized over a stick circuit passing from terminal B through front contact 14 of relay 1TR, front contact 15 of relay 2TR, front contact 16 of relay 3TR, front contact 17 of relay CR and the winding of relay CR to terminal C. A first pick-up circuit for relay CR is governed by each of the track and auxiliary relays, and may be traced from terminal B through front contact 9 of relay 2TR, front contact 18 of relay 1TR, front contact 19 of relay 1TPS, front contact 20 of relay 3TR, front contact 21 of relay 3TPS, and the winding of relay CR to terminal C. At times, however, the track relay 1TR or 3TR for the outer track section D—E or F—G, and the associated auxiliary relay 1TPS or 3TPS, are prevented in a manner to be explained presently from controlling the pick-up circuit for relay CR.
- 25 The immediate operating circuit for signal S passes from terminal B through back contact 22 of relay CR, and the winding of signal S to terminal C, so that signal S operates whenever relay CR is released.
- 30 The reference characters 1SR and 3SR designate directional stick relays, one for each of the track relays 1TR and 3TR for the outer track sections D—E and F—G. Relay 1SR is provided with a pick-up circuit passing from terminal B through back contact 5 of relay 1TR, front contact 23 of relay 3TPS, back contact 24 of relay 3SR, and the winding of relay 1SR to terminal C. A first stick circuit for relay 1SR may be traced from terminal B through back contact 9 of relay 2TR, front contact 25 of relay 1SR, and the winding of relay 1SR to terminal C; and a second stick circuit for relay 1SR passes from terminal B through back contact 7 of relay 3TR, front contact 26 of relay 1TPS, front contact 27 of relay 45 1SR, and the winding of relay 1SR to terminal C. The relay 3SR is provided with a pick-up circuit passing from terminal B through back contact 7 of relay 3TR, front contact 26 of relay 1TPS, back contact 27 of relay 1SR, and the winding of relay 3SR to terminal C. A first stick circuit for relay 3SR passes from terminal B through back contact 9 of relay 2TR, front contact 28 of relay 3SR, and the winding of relay 3SR to terminal C; while a second stick circuit for relay 50 3SR passes from terminal B through back contact 5 of relay 1TR, front contact 23 of relay 3TPS, front contact 24 of relay 3SR and the winding of relay 3SR to terminal C. When energized, relay 1SR or 3SR prevents relays 3TR and 3TPS, or relays 1TR and 1TPS, respectively, from controlling the pick-up circuit for relay CR, by providing an alternate path around the control contacts of those relays interposed in the pick-up circuit for relay CR. That is to say, 55 when relay 1SR is picked up to close front contact 29 a path is established around front contact 20 of relay 3TR and front contact 21 of relay 3TPS, which contacts as pointed out previously are normally included in the pick-up circuit for relay CR, the pick-up circuit for the operating relay CR in this latter event including front contact 9 of relay 2TR, front contact 18 of relay 1TR, front contact 19 of relay 1TPS, then front contact 29 of relay 1SR, and the winding of relay CR. When relay 3SR is energized

to close its front contact 30, an alternate path is established around front contact 18 of relay 1TR and front contact 19 of relay 1TPS, which contacts are normally included in the pick-up circuit for relay CR. The pick-up circuit for relay CR in this latter event includes front contact 9 of relay 2TR, front contact 30 of relay 3SR, front contact 20 of relay 3TR, front contact 21 of relay 3TPS, and the winding of relay CR. These alternate paths provided by relays 1SR 10 and 3SR, as will be explained in detail presently, cooperate with the track relays 1TR, 2TR and 3TR to provide directional control of signal S, whereby relay 1SR or 3SR, as the case may be, prevents trains operating in the eastbound or westbound direction, respectively, from controlling the signal after such trains have crossed the intersection and vacated section E—F.

The apparatus is in its normal condition, as shown in the drawing when no trains are operating on the stretch of railway track intermediate the points D and G. In this normal condition of the apparatus, the relays 1TR, 2TR, 3TR, 1TPS, 3TPS and CR are energized, and the relays 1TER, 3TER, 1SR, 3SR and signal S are 25 deenergized.

Having thus described the apparatus embodying my invention, I shall first explain the operation of the apparatus for a train which enters an outer section in approaching the intersection 30 and continues to operate in the same direction so that it crosses the intersection and passes through the other outer control section. Assuming, for example, that an eastbound train, that is, a train operating from left to right in the 35 drawing, enters section D—E in approaching the intersection, then relay 1TR is shunted and releases to open front contacts 5, 14 and 18, and to close its back contact 5. The opening of front contacts 14 and 18 opens respectively the stick and pick-up circuits for relay CR, with the result that relay CR releases to close its back contact 22, thereby initiating the operation of signal S, which now exhibits its warning indication to highway users of the approach of the train. The 40 opening of front contact 5 of relay 1TR opens the stick circuit for auxiliary relay 1TPS, with the result that relay 1TPS releases to open its front contact 19 interposed in the pick-up circuit for relay CR, and the closing of back contact 5 of 45 relay 1TR completes the previously traced pick-up circuit for stick relay 1SR, whereupon relay 1SR becomes energized to close its front contact 29.

In the event a momentary loss of train shunt 55 occurs while the train occupies section D—E, the track relay 1TR might pick up, following the fluctuation in the train shunt, but the operation of the control device, that is, signal S is unaffected, since relay 1TR ordinarily will release 60 prior to relay 1TPS picking up to complete the pick-up circuit for relay CR. That is to say, if relay 1TR picks up on a momentary loss of shunt in section D—E, to close at front contact 5 the energizing circuit for relay 1TER, relay 1TER 65 must be energized for its predetermined time interval before contact 12 of relay 1TER is closed. When contact 12 of relay 1TER is closed, and in the event that relay 1TR is not released due to the restoration of the train shunt in section D—E, 70 then the previously traced second pick-up circuit for relay 1TPS is established, with the result that relay 1TPS picks up to close front contact 19 and thereby complete the pick-up circuit for the operating relay CR. However, relay 1TR remains 75

ing picked up for the full interval of time required by relay 1TR to close its contact 12 is a very remote possibility, since ordinarily a loss of train shunt within a control section is of very few seconds in duration, so that the train shunt is normally restored and relay 1TR released prior to the pick-up circuit for relay CR being completed, with the result that the operation of signal S is unaffected by the picking up and releasing of relay 1TR in response to variations in train shunt in the control section. It should be pointed out that relay 1SR might be alternately energized and deenergized in step with the picking up and releasing of the relay 1TR in response to the varying train shunt, but this operation of relay 1SR at this time is immaterial.

When the eastbound train enters section E—F, relay 2TR is shunted and releases to open front contact 9 which is interposed in the pick-up circuit for relay CR, and to close back contacts 9, 31 and 32. The closing of back contact 9 of relay 2TR completes the previously traced first stick circuit for relay 1SR, so that relay 1SR is maintained energized over its first stick circuit while the train occupies section E—F. Relay 2TR also completes at its back contacts 31 and 32, respectively, the first pick-up circuit for relay 1TPS and 3TPS, with the result that relay 1TPS is energized and closes front contacts 6, 19 and 26 interposed respectively in the stick circuit for relay 1TPS, the pick-up circuit for relay CR, and the second stick circuit for relay 1SR.

When the train enters section F—G, relay 3TR releases to close its back contact 7, thereby completing the second stick circuit for relay 1SR, and to open the stick circuit for relay 3TPS at front contact 7. Relay 3TPS, however, remains energized over its previously traced first pick-up circuit including back contact 32 of relay 2TR. Front contacts 16 and 20 of relay 3TR interposed respectively in the stick and pick-up circuits for relay CR, are also opened when relay 3TR releases.

When the train vacates section D—E, relay 1TR picks up to close front contact 18 interposed in the pick-up circuit for relay CR to prepare that circuit, and to close at front contact 5 of relay 1TR the stick circuit for relay 1TPS. With relays 1TR, 1TPS and 1SR energized, the operation of signal S is maintained while the train occupies section E—F by virtue of the fact that relay 2TR is released and holds open front contact 9, which is interposed in the pick-up circuit for relay CR.

When the train vacates section E—F, relay 2TR picks up to close front contact 9, thereby completing the pick-up circuit for relay CR including front contact 29 of relay 1SR, with the result that relay CR picks up and opens at its back contact 22 the operating circuit for signal S and signal S now ceases to display its warning indication to highway users. Relay 2TR also opens its back contact 32 to open the first pick-up circuit for relay 3TPS, with the result that relay 3TPS releases to open its front contact 21 interposed in the pick-up circuit for relay CR, but as was pointed out hereinbefore, the pick-up circuit for relay CR is provided with an alternate path around front contact 21 of relay 3TPS and front contact 20 of relay 3TR, which alternate path includes closed front contact 29 of relay 1SR.

With relay 1SR energized over its second stick circuit including front contact 26 of relay 1TPS and back contact 7 of relay 3TR, it is obvious

that relay 1SR is maintained energized while the train occupies section F—G, with the result that relays 3TR and 3TPS are removed from control of signal control relay CR and of signal S. It follows that with relay 1SR energized, a train occupying section F—G in receding from the intersection is prevented from effecting the operation of signal S.

When the train vacates section F—G, relay 3TR picks up to close front contacts 16 and 20 interposed respectively in the stick and pick-up circuits for relay CR, to open its back contact 7, and to close its front contact 7. The opening of back contact 7 of relay 3TR opens the second stick circuit for relay 1SR, with the result that relay 1SR releases to open its front contact 29 included in the alternate path in the pick-up circuit for relay CR around front contact 21 of relay 3TPS, which contact is still open. Relay CR, as was pointed out previously, is slightly slow releasing so that front contact 16 of relay 3TR closes to complete the stick circuit for relay CR prior to relay CR releasing and opening its front contact 17 interposed in this stick circuit for relay CR, with the result that relay CR remains energized to prevent operation of signal S. With front contact 7 of relay 3TR and back contact 11 of relay 3TPS closed, the previously traced circuit for energizing relay 2TER is completed whereupon relay 2TER at the end of its predetermined time interval closes its contact 13 to complete the second pick-up circuit for relay 3TPS. Relay 3TPS now picks up to close its front contacts 8 and 21 interposed respectively in the stick circuit for relay 3TPS and the pick-up circuit for relay CR, and to open at its back contact 11 the energizing circuit for relay 3TER, which becomes deenergized to open its contact 13. The apparatus is now restored to its normal condition.

I shall now explain the operation of the apparatus embodying my invention for a train which enters an outer control section in approaching the intersection after another train has entered the other outer control section in approaching the intersection, but which other train reverses its direction and vacates the associated outer control section. Assuming that a westbound train, that is, a train operating from right to left in the drawing, first enters section F—G in approaching the intersection, relay 3TR is shunted and releases to open front contacts 7, 16 and 20. The opening of front contacts 16 and 20 interposed respectively in the stick and pick-up circuits of relay CR, results in relay CR releasing to complete the operating circuit for signal S, whereupon the operation of signal S is initiated. The opening of front contact 7 of relay 3TR opens the previously traced stick circuit for relay 3TPS, with the result that relay 3TPS releases to open its front contact 21 interposed in the pick-up circuit for relay CR, while the closing of back contact 7 of relay 3TR completes the pick-up circuit for relay 3SR, whereupon relay 3SR picks up to close front contact 30.

Then, when an eastbound train enters section D—E in approaching the intersection, relays 1TR and 1TPS become released to open respectively front contacts 18 and 19 interposed in the pick-up circuit for relay CR, and relay 1TPS also opens front contact 26 interposed in the pick-up circuit for relay 3SR whereupon relay 3SR releases, so that relay 3SR no longer provides an alternate path including its front contact 30 around contacts 18 and 19 of relays 1TR and 1TPS inter-

posed in the pick-up circuit for relay CR. With the pick-up circuit for relay CR opened at front contacts 18 and 19 of relays 1TR and ITPS, it follows that when the westbound train reverses direction in section F—G and vacates section 5 F—G at its right-hand end, so that relay 3TR immediately picks up to close its front contact 20 interposed in the pick-up circuit for relay CR, and relay 3TPS is caused to pick up, as will be 10 explained hereinafter, to close its front contact 21 interposed in the pick-up circuit for relay CR, the operation of relay CR and of signal S is not affected, and the second train maintains the operation of the signal S which has been initiated 15 by the first or westbound train entering the other control section F—G. Thus, when the westbound train backs out of section F—G and relay 3TR closes its front contact 20 as pointed out above, relay 3TR also closes at its front contact 7 the 20 energizing circuit for relay 3TER. At the end of its predetermined time interval, relay 3TER closes its contact 13 with the result that the second pick-up circuit for relay 3TPS is completed whereupon relay 3TPS picks up to close front 25 contacts 21 and 23 interposed respectively in the pick-up circuits for relay CR and relay 1SR. With front contact 23 of relay 3TPS and back contact 5 of relay 1TR closed, relay 1SR picks up to close its front contact 29. The apparatus 30 is now conditioned by the presence of the train in section D—E, to maintain operation of the signal S for further operation of the train until that train clears the intersection and vacates section E—F, and to prevent operation of the 35 signal while the train recedes from the intersection through the outer section F—G, in the manner described in detail previously for the operation of the apparatus for an eastbound train.

The operation of the apparatus embodying my 40 invention for a westbound train operating across the intersection and through the outer section D—E on the other side of the intersection is substantially similar to the operation previously described for an eastbound train, and it is believed, therefore, that this latter operation will be readily apparent from the foregoing description together with an inspection of the drawing without further detailed explanation.

Although I have herein shown and described 50 only one form of apparatus embodying my invention, it is understood that various changes and modifications may be made therein within the scope of the appended claims without departing from the spirit and scope of my invention.

Having thus described my invention, what I 55 claim is:

1. In combination, a stretch of railway track divided into two outer sections and an intermediate section, said intermediate section being intersected by a highway and provided with a highway crossing signal located at such intersection, a track circuit including a track relay for each section, two auxiliary relays one for each track relay for the outer sections, operating means 60 governed jointly by said track relays and by said auxiliary relays for causing said signal to operate for railway traffic moving in either direction in said intermediate section but to operate for railway traffic moving only toward the intermediate section in said two outer sections, and means 65 governed by each track relay for the outer sections for controlling the associated auxiliary relay to prevent a momentary loss of train shunt in an outer section from effecting loss of operation of said signal.

2. In combination, a stretch of railway track divided into two outer sections and an intermediate section, said intermediate section being intersected by a highway and provided with a highway crossing signal located at such intersection, a 5 track circuit including a track relay for each section, two auxiliary relays one for each track relay for the outer sections, operating means governed jointly by said track relays and by said auxiliary relays for causing said signal to operate for railway traffic moving in either direction in said intermediate section but to operate for railway traffic moving only toward the intersection in said two outer sections, two time element relays one for each auxiliary relay, means for 10 controlling each of said time element relays governed by its associated auxiliary relay and the track relay associated therewith, and means governed by each time element relay for preventing a loss of train shunt within its associated outer section from effecting loss of operation of said signal.

3. In combination, a stretch of railway track divided into three sections, a track relay for each section, a signal, a signal operating relay normally energized over a stick circuit including a front contact of each of said track relays, two auxiliary relays one associated with each of two of said track relays, a pick-up circuit for said signal operating relay including a front contact of each of said track relays and a front contact of each of said auxiliary relays, and means governed by each of said two track relays for controlling its associated auxiliary relay to prevent a momentary loss of train shunt in the section for that track relay from effecting loss of operation of said signal.

4. In combination, a stretch of railway track divided into three sections, a track relay for each section, two auxiliary relays one associated with 40 each of two of said track relays and each auxiliary relay normally energized over a stick circuit including a front contact of its associated track relay, two time element relays one for each auxiliary relay, an energizing circuit for 45 each time element relay including a back contact of its associated auxiliary relay and a front contact of the track relay associated therewith, a pick-up circuit for each auxiliary relay including a front contact of each of said track relays and a front contact of each of said auxiliary relays, and two directional stick relays one for each direction and controlled by said two track relays for at times preventing the associated track relay from controlling said 50 signal operating relay.

5. In combination, a stretch of railway track divided into three sections, a track relay for each section, two auxiliary relays one associated with each of two of said track relays and each auxiliary relay normally energized over a stick circuit 65 including a front contact of its associated track relay, two time element relays one for each auxiliary relay, an energizing circuit for each time element relay including a back contact of its 70 associated auxiliary relay and a front contact of the track relay associated therewith, a pick-up circuit for each auxiliary relay including a front contact of its associated track relay and a contact of its associated time element relay closed in 75

- 5 a predetermined period after energization thereof, a signal, a signal operating relay normally energized over a stick circuit including a front contact of each of said track relays, a pick-up circuit for said signal operating relay including a front contact of each of said track relays and a front contact of each of said auxiliary relays, and two directional stick relays one for each direction and controlled by said two track relays 5 for at times preventing the associated track relay and its associated auxiliary relay from controlling the pick-up circuit for said signal operating relay.
- 10 6. In combination, a stretch of railway track divided into three sections, a track relay for each section, two auxiliary relays one associated with each of two of said track relays and each auxiliary relay normally energized over a stick circuit including a front contact of its associated track 10 relay, two time element relays one for each auxiliary relay, an energizing circuit for each time element relay including a back contact of its associated auxiliary relay and a front contact of the track relay associated therewith, a pick-up 15 circuit for each auxiliary relay including a front contact of its associated track relay and a contact of its associated time element relay closed in a predetermined period after energization thereof, a signal, a signal operating relay, circuit means for controlling said signal operating relay including a front contact of each of said track relays and a front contact of each of said auxiliary relays, two directional stick relays one for each direction and controlled by said two track relays for at 20 times preventing the associated track relay from controlling said signal operating relay.
- 20 7. In combination, a stretch of railway track divided into three sections, a track relay for each section, a signal, a signal operating relay normally energized over a stick circuit including a front contact of each of said track relays, two auxiliary relays one associated with each of two of said track relays and each auxiliary relay normally energized over a stick circuit including a front contact of its associated track relay, a 25 first pick-up circuit for each auxiliary relay governed by the third one of said track relays, a pick-up circuit for said signal operating relay governed by a front contact of each of said track 25 relays and auxiliary by a front contact of each of said relays, two directional stick relays one for each direction and controlled by said two track relays for at times rendering the associated track relay and its associated auxiliary relay ineffective to govern the pick-up 30 circuit for said signal operating relay, two time element relays one for each of said auxiliary relays, an energizing circuit for each time element relay including a back contact of its associated auxiliary relay and a front contact of the 30 track relay associated therewith, and a second pick-up circuit for each auxiliary relay including a contact of its associated time element relay closed in a predetermined period after energization thereof, whereby the picking up of a track 35 relay in response to a loss of shunt within its control section is ineffective to govern the pick-up circuit for said signal operating relay. 35
- 40 8. In combination, a stretch of railway track divided into three sections, a track relay for each section, two auxiliary relays one associated with each of two of said track relays and each auxiliary relay normally energized over a stick circuit including a front contact of its associated track relay, a first pick-up circuit for each auxiliary relay governed by the third one of said track 40 relays, two time element relays one for each auxiliary relay, an energizing circuit for each 45

GEORGE R. PFLASTERER.

CERTIFICATE OF CORRECTION.

Patent No. 2,175,408.

October 10, 1939.

GEORGE R. PFLASTERER.

It is hereby certified that error appears in the printed specification of the above numbered patent requiring correction as follows: Page 5, second column, line 30, claim 8, strike out the word "auxiliary" and insert the same after "said" in line 31, same claim; and that the said Letters Patent should be read with this correction therein that the same may conform to the record of the case in the Patent Office.

Signed and sealed this 14th day of November, A. D. 1939.

(Seal)

Henry Van Arsdale,
Acting Commissioner of Patents.
